UNITED STATES PATENT OFFICE

HERMAN S. TABOR, OF CHICAGO, ILLINOIS

DESIGN FOR A FONT OF TYPE OR A SIMILAR ARTICLE

Application filed September 21, 1931. Serial No. 41,171. Term of patent 7 years.

To all whom it may concern:

Be it known that I, HERMAN S. TABOR, a citizen of the United States, and a resident of the city of Chicago, in the county of Cook and State of Illinois, have invented a new, original, and ornamental Design for a Font of Type or a Similar Article, of which the following is a specification, reference being had to the accompanying drawing, forming a part thereof.

In the drawing:

The figure illustrates a perspective view of the font of type or similar article, embodying my invention.

I claim:

The ornamental design for a font of type or a similar article, as shown.

HERMAN S. TABOR.
